UNITED STATES PATENT OFFICE.

SADIE HASSLER AND VICTOR HASSLER, OF PHILADELPHIA, PENNSYLVANIA.

SKIRT MARKER.

Application filed January 7, 1926. Serial No. 79,709.

The object of this invention is to devise a novel construction and arrangement of a skirt marker by the use of which a skirt, dress or coat can have the bottom uniform 5 by being marked or pinned, so that it will be the desired distance from the ground.

Another object in view is to devise a novel skirt marker which can be economically manufactured and which can be used 10 by the ordinary house-wife.

With the above and other objects in view, as will hereinafter more clearly appear, our invention comprehends a novel construction and arrangement of a skirt marker.

15 It further comprehends a novel skirt marker having a plurality of standards, one of which is graduated. One of said standards carries a curved back plate which is vertically adjustable on it, and the other 20 of said standards carries a fitting on which a curved clamping bar is laterally adjustable and between said bar and plate the goods of the skirt, dress or coat are clamped. The clamping bar serves as a support for 25 the crayon or pencil which is used to mark the skirt, coat or dress.

Other novel features of construction and advantage will hereinafter more clearly appear in the detailed description and the 30 appended claims.

For the purpose of illustrating the invention, we have shown in the accompanying drawing a typical embodiment of it, which, in practice, will give reliable and satisfactory results. It is, however, to be understood that this embodiment is typical only and that the various instrumentalities of 35 which our invention consists can be variously arranged and organized, and the invention is not, therefore, limited to the precise arrangement and organization of these instrumentalities as herein set forth.

Figure 1 is a perspective view of a skirt marker embodying our invention.

45 Figure 2 is a top plan view.

Similar numerals of reference indicate corresponding parts.

Referring to the drawings:—

1 designates a skirt marker embodying our 50 invention. The skirt marker is provided with a base 2, from which rise the posts or standards 3 and 4, respectively.

The standard 4 is provided with a vertically extending groove 5, and is adapted to 55 receive a collar 6, which is secured in its

vertically adjusted position by means of a set screw 7 which is adapted to enter the groove 5, so that the backing plate 8, secured to the collar 6, will always be held in proper alignment.

The other post 3 is provided with a vertically extending groove 9, and is adapted to receive a collar 10 which is secured in aligned position by means of a set screw 11, the forward end of which passes into the 65 groove 9.

The collar 10 has extending from it a tubular arm 12 into which extends a post 13, which is fixed to a clamping bar 14. The tubular arm 12 is slotted as at 15 to receive a bar 16 which closely fits the slot and forms a grasping handle. The post 3 has the graduations 17 to accurately indicate the height to which the clamping bar 14 has been raised.

In the operation the back plate 8 and clamping bar 14 are adjusted to the desired height on their standards and the set screws are tightened. The skirt, dress or coat is inserted between the back plate and 75 the clamping bar, and the clamping bar is moved forwardly to clamp the goods.

The goods are pinned along the top of the clamping bar, or a mark is made with a crayon or pencil by drawing it along the 80 clamping bar.

The clamping bar 14 is now moved rearwardly, the person to be fitted changes her position, and the clamping bar 14 is again moved forwardly and the proper indications 85 made on the skirt, dress or coat.

The operation is continued until the entire bottom portion of the skirt, dress or coat is marked.

Special attention is directed to the adjustable feature of the clamping bar, since it can be adjusted so that it will take in fabric of thick material such as is used in women's coats, and can also be used for the sheerest kind of dress goods.

The backing plate forms an abutment for marking, and the clamping bar defines an accurate line along which the mark can be made.

Due to the provisions of the vertical slots 105 in the standards, the back plate and clamping bar are always retained in the proper relationship to each other.

Our present construction of skirt marker can be very economically manufactured, 110

and the adjustments and the manner in which it is used are self evident from the construction.

Having thus described our invention 5 what we claim as new and desire to secure by Letters Patent, is:

1. In a skirt marker, a base, standards rigidly connected with said base, graduations on one of said standards, a collar vertically adjustable on one of the standards, 10 a tubular slotted arm on said collar, a clamping bar having a post to fit within said arm, a grasping handle extending through said slot and secured to said post, and a backing plate vertically adjustable 15 on the other of said standards.

2. In a skirt marker, a base, a pair of standards, one of which is graduated, fixed to said base, said standards each having vertical aligning slots, a curved plate, a 20 collar in one of said standards adapted to enter the slot in said first named standards and secure said plate in aligned position, a fitting having a laterally extending slotted arm on the other of said standards, a set 25 screw to enter the slot of the second standard to secure the fitting in aligned position, a clamping bar having a post adjustable on said arm, and a grasping handle extending through said slot and secured to said post.

SADIE HASSSLER.
VICTOR HASSSLER.
